United States Patent Office

Des. 222,328

Patented Oct. 19, 1971

222,328

HANDLE

John S. Vecchione, Sturbridge, Mass., assignor to Parker
Manufacturing Company, Worcester, Mass.

Filed June 17, 1970, Ser. No. 23,529

Term of patent 14 years

Int. Cl. D8—01

U.S. Cl. D8—5

FIG. 1 is a plan view of a handle, showing my new design,

FIG. 2 is another plan view of the handle,

FIG. 3 is a front elevational view of the handle,

FIG. 4 is a back elevational view of the handle,

FIG. 5 is an end view of the handle,

FIG. 6 is an opposite end view of the handle,

FIG. 7 is a sectional view of the handle taken on the line 7—7 of FIG. 2, and

FIG. 8 is a sectional view of the handle taken on the line 8—8 of FIG. 2.

The broken lines are shown for illustrative purposes only and do not form part of the claimed design.

I claim:

The ornamental design for a handle, as shown and described.
